UNITED STATES PATENT OFFICE.

PAUL KUHNE, OF BIRMINGHAM, ALABAMA, ASSIGNOR OF ONE-HALF TO WERNER KUHNE, OF BIRMINGHAM, ALABAMA.

BALE-TIE.

1,287,347.

Specification of Letters Patent. Patented Dec. 10, 1918.

Application filed June 10, 1918. Serial No. 239,203.

To all whom it may concern:

Be it known that I, PAUL KUHNE, a citizen of the United States of America, residing at Birmingham, in the county of 5 Jefferson and State of Alabama, have invented certain new and useful Improvements in Bale-Ties, of which the following is a specification.

This invention relates to improvements 10 in bale ties.

Heretofore bale ties have been made with open slots to receive the band; in some instances the open portion of the slot is parallel with the pull exerted, and in others, it 15 is at right angles to the pull. It is the latter form of tie to which my invention is directed. In practice, when pull is exerted on the band, and because of the open end of the slot, the body portion of the tie 20 breaks open, and considerable difficulty has been experienced in this direction, although the open end structure is by far preferable and more convenient for the insertion of the band.

25 The prime object of this invention is to provide a flange in line with the open portion of the slot, and strengthen the tie in parallel relation with the pull exerted when applying a band adjacent the flange 30 whereby when pull is applied in opposite directions, the strain is centralized in line with the flange and the opening leading to the slot. It follows, therefore, that the flange not only serves as a means for locating the band in the slot, but it very materially adds to the strengthening of the 35 corrugated portion of the body at the point where the strain is centralized.

With these and other objects the invention 40 comprehends improvements in the details of construction and arrangement of parts which will be hereinafter described and particularly pointed out in the claim.

In the drawings—

45 Figure 1 is a perspective view of my improved bale tie.

Fig. 2 is a section of same on the line $x-x$, of Fig. 1.

1 indicates a metal body portion formed 50 with a slot 2, open at one end at 3. The sides of the body portion taper, forming somewhat the shape of a key stone.

The wall of the slot adjacent the opening 3, is extended to provide flanges 4, and 55 the opposite wall of said slot is provided

with a central extension to form a flange 5, which is in alinement with the opening 3. The edges of the respective flanges taper toward the side walls of the slot to form seats for the bent ends of the band. 60

The body portion of the tie between the flange 5, and the outer edge is corrugated, the corrugations being disposed parallel to the short walls of the slot, or in parallel relation to the pull exerted by the bands 65 when tying a bale.

In operation, the bent ends of a band are inserted through the opening 3, and are moved down in the opposite seats adjacent the side walls of the slot. When pull 70 is exerted on the band, owing to the opening 3, the entire strain is thrown on the body portion beyond the flange 5. As the pull on the band is in opposite directions, the strain produced tends to split or open 75 the body portion, somewhat like the action of a hinge. This results in the forces being toward each other, or in direction of a line drawn through the flange 5, and the opening 3. But by corrugating the metal, 80 buckling, or breaking on this imaginary line is avoided, inasmuch as the corrugations act to increase the resistance. It is obvious that the corrugations add strength to that part of the body portion where the 85 greatest strain occurs, and furthermore the flange 5, in addition to serving as a guide for the band, lends additional strength to the device at the weakest point in the structure. It follows therefore, that the tie is 90 reinforced or strengthened at the point of greatest strain, and at a centralized point midway between the bands and in line with the opening leading to the slot.

The tapered sides of the tie assist in performing an important function in this invention, inasmuch as the gradual increase in the length of the corrugations adds metal, and therefore increases the resistance of the strains at the outer edge of the body portion. The edge of the tie where the corrugations are formed has to resist all the strain to prevent the metal breaking at the flange 5. This contingency, however, is met by the increased length of the corrugations at this point; consequently the body portion is effectually prevented from breaking when the tie is in use. 100

What I claim is:

110 A bale tie comprising a sheet metal body

portion the sides of which converge from the top to the bottom, the body portion having a slot which opens through the narrow bottom edge, said body portion being corrugated at right angles to the opening leading to the slot between the edge wall of said slot and the outer edge of said portion, the corrugations being arranged in lines parallel to the pull exerted by bands inserted in the slot, whereby to centralize the strain in line with the opening and gradually increase the resistance to said strain toward the edge of the body portion.

In testimony whereof I affix my signature.

PAUL KUHNE.
